UNITED STATES PATENT OFFICE.

EDWIN S. WOODS, OF CHICAGO, ILLINOIS; ALBERT G. WELCH, EXECUTOR OF SAID EDWIN S. WOODS, DECEASED, ASSIGNOR TO ALBERT G. WELCH, TRUSTEE.

ANTIFRICTION-BEARING.

1,213,991.

Specification of Letters Patent. Patented Jan. 30, 1917.

Application filed April 12, 1913. Serial No. 760,632.

To all whom it may concern:

Be it known that I, EDWIN S. Woods, a citizen of the United States, and a resident of Chicago, in the county of Cook and State of Illinois, have invented certain new and useful Improvements in Antifriction-Bearings; and I do hereby declare that the following is a full, clear, and exact description thereof, reference being had to the accompanying drawings, and to the letters of reference marked thereon, which form a part of this specification.

This invention relates to improvements in antifriction bearings designed to transmit load between two parts capable of limited relative movement and is shown herein as applied to a side-bearing more particularly intended for use in connection with railroad cars.

The invention consists of the matters hereinafter described and more particularly pointed out in the appended claims.

The improved antifriction bearing is of that type in which the antifriction element is carried by the lower one of the two parts between which the bearing transmits load, that is to say, in the case of a railroad car in which the antifriction bearing is carried by the truck-bolster.

In the drawings: Figure 1 is a view representing a longitudinal central section through my improved antifriction bearing. Fig. 2 is a top plan view of the same. Fig. 3 is a view representing a transverse section through the bearing in a plane indicated by the line 3—3 of Fig. 1. Fig. 4 is a view representing a longitudinal central section through a modified form of the improved bearing. Fig. 5 is a top plan view of the construction shown in Fig. 4. Fig. 6 is a view representing a transverse section through the construction shown in Fig. 4 in a plane indicated by the line 6—6 thereof.

Referring now to that embodiment of my invention shown in the drawings, and particularly to that shown in Figs. 1 to 3, inclusive, 10 indicates a casing made integral with and extending transversely of a truck-bolster 11 which may be in the form of a channel or other suitable beam construction. The casing 10 is of elongated, rectangular cross-section and has upright end

walls 12, 12 and upright side walls 13, 13, which rise from the top of the truck-bolster. The top member 11^a of the beam forming the truck-bolster, that is to say, that part of said top member inclosed by the four upright walls of the casing comprises the bottom wall of said casing.

14 indicates a rocker of substantially the length of the casing and placed therein so as to be capable of a rocking movement on the bottom wall 11^a of the casing, said rocker is of substantially the width of the space between the side walls 13, 13 of the casing which co-act with it in guiding relation to maintain the rocker in proper position during its rocking movement and when it is at rest. As shown herein, the rocker is recessed on its upper side to provide a longitudinally extending chamber 15 having side walls 16, 16, a bottom wall 17, and curved end walls 18, 18. In this chamber is contained the antifriction elements which, as illustrated herein, consist of a cylindric roller 19 having flat ends 20. Said roller is preferably provided with apertures or openings 21 to lighten its weight.

In the bottom wall of the chamber in the rocker is placed a wear-plate of hardened metal, 22, which is of sufficient length to offer a bearing for the antifriction element throughout the full length of its travel in either direction from the center of the rocker. The upper surface of said wear-plate is inclined upwardly toward each end of the rocker from a transverse median line 23. The end walls 18 of the chamber formed by the recess in the upper side of the rocker, are curved to fit the curved surface 90 of the antifriction element when it has reached the end of its possible movement in said chamber. The side walls 16, 16 of the chamber, lying closely adjacent to the flat ends of the antifriction element, as shown in Fig. 3, act to guide said antifriction element in its rolling movement and maintain it with its axis of rotation at right angles to the direction of its travel on the rocker.

The rocker 14 is provided with means 100 which co-acts with means in the casing to maintain it in its proper longitudinal position in the casing, both when at rest and in its rocking movement. That is to say,

means which prevents the rocker from displacement toward one or the other end of the casing. As shown in Figs. 1 to 3, this means consists of a transverse wedge-shaped 5 rib 25 located on the middle of the bottom surface of the rocker, and of a transverse groove or opening 26 in the bottom wall of the casing with the side walls of which said rib engages. As will presently appear the 10 maximum rocking movement of the rocker will not lift this rib entirely from the groove or opening in which it engages, so that apparently the rocker will be maintained in its relative longitudinal position in the casing. 15 On each side of the rib 25 the bottom of the rocker is formed with transverse flat faces 27, 27 which are in a plane at right angles to a vertical diameter of the anti-friction element, when said antifriction ele- 20 ment is in a central or other predetermined normal position of rest on the rocker. Beyond said flat surfaces 27, 27, the bottom of the rocker has upwardly inclined flat surfaces 28, 28, said upwardly inclined flat sur- 25 faces meeting the first named horizontal flat surfaces in transverse line of intersection 29 located at predetermined equal distances at either side of the median line of the rocker. Manifestly when the rocker is 30 tipped toward one end of the casing or the other end of the casing it will rock upon one or the other transverse ridges defined by the lines 29 in which the several surfaces referred to meet. 35 The operation of the bearing is as fol- lows: When the body-bolster, indicated at 30, engages the antifriction element and rolls it, by reason of the relative move- 40 ment between the body and truck-bolsters, toward one end of the rocker, as soon as the antifriction element passes toward the end of the casing to a point beyond a point vertically above one of the fulcrum ridges 29, the rocker 14 will be rocked on said ridge 45 so as to bring the associated face 28 into flat bearing against the bottom wall of the casing, as indicated in dotted lines in Fig. 1. As soon as the antifriction element is released, the opposite end of the rocker, by 50 reason of its weight will cause the rocker to rock on the ridge 29 back into its normal position with the central flat bearing sur- 55 faces 27, 27 in flat engagement with the bottom wall of the casing, as shown in full lines. The antifriction element will then roll down the incline of the wear-plate toward the central or normal position on the rocker. It will be noted in this connection that the inclined wear faces of the wear- 60 plate are made parallel to the inclined bottom faces 28 of the rocker, so that the anti-friction element will roll on a horizontal surface, that is to say, one parallel to the bottom face of the body bolster, when the

rocker has been rocked into the position in- 65 dicated in dotted lines.

While I have referred to the bearing sur- 70 faces 27 and 28 of the rocker as flat, it will be understood that I mean by said term, that the said surfaces are substantially flat only, since the surface of the rocker intermediate the transverse ends of said flat sur- 75 faces may be cut away as indicated at 31, to lighten the construction of the rocker.

The bottom wall of the casing, that is to 80 say, the top member of the truck-bolster at the casing, is provided with slots or open- 85 ings 32 to permit the cinders, dust and the like that may collect in the bearing to fall through and thus be discharged from the casing. The rocker is provided with inclined ventilation openings 33 for a like purpose and preferably the end and side walls of the casing are provided with venti- 90 lation openings 34.

In Figs. 4 to 6, inclusive, I have shown a slightly modified form on construction, in which like parts are indicated by the same numerals of reference. In this case, I pro- 95 vide a casing separate from the truck- 100 bolster, the same consisting of a shell 35 of suitable cross-section and having laterally extending ears 36^a at its base for at- 105 tachment to the top of the truck-bolster. Said casing has side walls 36, 36, and end walls 37, 37, as before, but in this case the end walls are carried above the level of the ends of the rocker and are provided with horizontal, overhanging flanges 38, 38, which act to loosely confine the rocker within the casing and prevent it from 110 bouncing out under the vibratory movement of the track. I also provide in this modified form of the bearing a slightly different means for retaining the rocker in its proper longitudinal position in the casing. The 115 rocker is provided at its bottom with laterally projecting studs or trunnions 39, the axes of which correspond with a transverse median line of the rocker. Said trunnions engage within downwardly opening grooves or notches 40 formed in the side walls of the casing. Manifestly the operation of the bearing modified as described is substantially the same as that described heretofore in connection with the bearing shown in 120 Figs. 1 to 3.

While in describing my invention I have referred to certain details of mechanical ar- 125 rangement and construction, it is to be un- 130 derstood that the invention is in no way limited thereby except as pointed out in the appended claims.

I claim as my invention:—

1. An antifriction bearing comprising a 125 rocker having a top bearing surface, a sup- 130 port for said rocker and an antifriction ele- 135 ment carried by said rocker having a pe-

- ripheral rolling bearing on said top bearing surface, said rocker having upwardly turned ends which limit the movement of said antifriction element, said upturned 5 ends having ventilation apertures, which open into said bearing surface and extend through said rocker.
2. An antifriction bearing comprising a rocker having oppositely inclined top bearing surfaces, intersecting in a transverse median line of the rocker, a support for said rocker, and an antifriction element having rolling bearing on said oppositely inclined top bearing surfaces of said rocker, said 10 bearing surfaces terminating at their outer ends in upwardly curved turned stop surfaces, adapted to be engaged by and to stop said antifriction element when at either limit of movement on said bearing surface.
- 20 3. An antifriction bearing comprising a rocker provided with a flat bearing surface at its middle and with oppositely inclined bearing surfaces, which terminate at their outer ends in upwardly turned stop surfaces, a support for said rocker, and an antifriction element having peripheral bearing on said bearing surfaces carried by said rocker and adapted to engage with and be arrested by said upwardly turned stop surfaces at either limit of its travel on said bearing surfaces.
4. An antifriction bearing comprising a rocker provided with a flat bearing surface on its bottom at the middle, and with inclined bearing surfaces at either end of said first named bearing surface, said rocker being provided on its top surface with oppositely inclined bearing surfaces parallel to the inclined bearing surfaces on the bottom 35 thereof, said oppositely inclined top bearing surfaces being curved upwardly at their outer ends, a support for said rocker, and an antifriction element carried on the top of said rocker.
- 45 5. An antifriction bearing comprising a rocker having oppositely inclined bottom bearing surfaces, and an intermediate horizontal bearing surface, said rocker having on its top oppositely inclined bearing surfaces 50 which curve upwardly at their outer ends, said surfaces intersecting in a transverse median line of the said intermediate bottom bearing surface, an antifriction element adapted for a rolling movement on said top bearing surfaces, and a support for said bottom bearing surfaces of said rocker.
6. An antifriction bearing comprising a rocker having oppositely inclined bottom bearing surfaces and an intermediate horizontal bearing surface, said rocker also having oppositely inclined top bearing surfaces which curve upwardly at their outer ends, said surfaces intersecting in a transverse line located about a transverse median line 60
- of said intermediate bottom bearing surface, said top and bottom inclined bearing surfaces being parallel, an antifriction element having rolling bearing on said top bearing surfaces, and a support for the bottom bearing surfaces of said rocker.
7. An antifriction bearing comprising a rocker provided with an open top chamber in its top surface, said chamber being defined by upright side and upwardly curved end walls, a support for said rocker, said support having apertures and a lug on said rocker adapted to engage within one of said apertures to prevent undue shifting of said rocker relative to said support.
8. An antifriction bearing comprising a rocker having a top bearing surface, the outer ends of which are curved upwardly to form end walls, and flanges at each side of said bearing surface, a cylindric antifriction element having flat ends carried by said rockers with its flat ends in guiding relation with said flanges, said antifriction element engaging either upward curved end wall when in either limit of its movement, a support for said rocker, said support having apertures and a lug on said rocker adapted to engage in one of said apertures to prevent undue shifting of the rocker relative to said support.
9. An antifriction bearing comprising a casing, a rocker in said casing, means confining said rocker to a predetermined longitudinal position in said casing, said rocker being provided with a top bearing surface and with longitudinally extending upright flanges at each side thereof, and with upwardly curved end walls, and a roller having flat ends, said roller having rolling bearing on the top of said rocker with its flat ends in guiding relation with said upright flanges of the rocker, said curved end walls forming stops to limit the rolling movement of said roller, and said rocker being constructed to tip in either direction when the roller passes a predetermined point on the rocker in rolling in that direction and to return to normal position when said roller is released from load.
10. An antifriction bearing comprising a casing, a rocker in said casing, an antifriction element having rolling bearing on top of said rocker, and means confining said rocker to a predetermined longitudinal position in said casing, said casing being provided with overhanging flanges at its ends adapted to loosely confine said rocker.
11. A side bearing for railway cars, comprising a rolling load supporting antifriction member, and a rolling member carried by the lower bolster and forming a bearing surface for said antifriction member and thereby receiving the load carried by said member.

12. A side bearing for railway cars, comprising a load supporting roller, and a rocking member arranged to roll with reference to the lower bolster and forming a bearing surface for coöperating with the load carrying surface of said roller.
13. A side bearing for railway cars, comprising a housing or frame carried by the lower bolster, an antifriction load carrying member movable in said housing, and a rolling member carried by the lower bolster and

having a bearing surface for coöperation with the load carrying surface of said anti-friction member.

In testimony, that I claim the foregoing as 15 my invention I affix my signature in the presence of two witnesses, this 7th day of April A. D. 1913.

EDWIN S. WOODS.
